SETTS, A CORPORATION OF MAINE.

DAMPING SYSTEM FOR MUSICAL INSTRUMENTS.

1,183,685.

Specification of Letters Patent.

Patented May 16, 1916.

Application filed July 21, 1910. Serial No. 573,135.

To all whom it may concern:

Be it known that we, GEORGE B. SINCLAIR, of Medford, and MELVIN L. SEVERY, of Arlington Heights, in the county of Middlesex and Commonwealth of Massachusetts, both citizens of the United States, have invented certain new and useful Improvements in Damping Systems for Musical Instruments, of which the following is a specification.

10 This invention relates more especially to that class of musical instruments wherein sonorous bodies, and particularly tuned strings, are vibrated either by means of hammers, or by electromagnets receiving properly-timed electric pulsations, or by means of both, as set forth in our companion applications Serial Nos. 273,199 and 745,400.

One of the especial purposes of this invention is the construction of electrically controlled means whereby a plurality of dampers may be applied to a single string and all simultaneously withdrawn from such string upon the depression of the key or the operation of the parts of the action associated 25 with said string. In actual practice, we prefer two dampers for each of the lower, or bass, strings of the instrument, one damper being located normally to damp the string at a point as close as possible to 30 where it is struck by its hammer, and the other damper being preferably located at a point equally distant from the other end of the string.

In certain co-pending applications we 35 have shown, described and claimed features which are illustrated and described in the present application, but which are not herein claimed, and in other co-pending applications we have broadly claimed the art of 40 producing musical tones, which art is involved but not claimed in the present application. All matters set forth and claimed in co-pending applications filed in our names, or in the name of either of us, and not specifically claimed herein, are expressly saved and reserved for one or another of such applications. Among these may be noted our joint applications Serial No. 273,199, filed August 7, 1905; Serial No. 379,714, filed 45 June 19, 1907; Serial No. 531,589, filed December 6, 1909; Serial No. 537,257, filed January 10, 1910; and Serial No. 745,400, filed January 31, 1913.

Referring to the drawings forming part of this specification, Figure 1 is a perspective view, more or less in diagram, of a musical instrument embodying our invention. Fig. 2 is a side sectional elevation of the auxiliary dampers, the same being shown on a larger scale. Fig. 3 is a face view of 60 said auxiliary dampers. Fig. 4 is a detail view of a wippen and associated parts.

In the following description and claims, we refer to a sonorous body or string irrespective of whether one or more such sonorous bodies or strings are employed to compose each note in the instrument, although it is the custom frequently to have either two or three strings to a note. The strings 1, to which our damping system is shown as applied, are of iron, steel or other magnetically attractive material, and are vibrated by means of electromagnets 2 to which electric pulsations are transmitted. The current for such purpose is received from the 75 source 3 through the pulsator consisting of the toothed rings 4 and brushes 5; and the circuit for the same comprises the wire 6, brush 7, toothed rings 4, brushes 5, wires 9, to said electromagnets 2, and from thence 80 through the wires 10 to the action rail 11, resistance 12, contacts 13, 14, brushes 15 and wire 16 back to said source.

Each key 17 by its depression at its outer end elevates a sticker 19, and by the latter's 85 engagement with the action of an associated hammer 20 throws said hammer percussively against a string 1. Each sticker is pivotally connected to a lever extension 21 at the free end of which is one of said 90 brushes 15, whereby the depression of a key moves its brush 15 up into touch with the associated contact 13, thereby switching a limited amount of current to an electromagnet 2, such limitation being due to said 95 resistance 12; and then such brush rises into touch with the upper associated contact 14 and so delivers full current to such electromagnet.

As thus far described, the actuation of a 100 key delivers both a percussive and also an electromagnetic set of vibrations to its associated string. To permit the depression of the keys to electrically vibrate the strings without the percussive action, the upper ends 105 of the stickers 19 are adapted to be with-

drawn from engagement with the wippens 29, as more fully set forth in our Patent No. 1,104,282, dated July 21, 1914.

The dampers 25 are pivotally supported 5 near the electromagnets 2, and each is withdrawn from its associated string or strings by means of a spoon 26 rising from a lever arm 27. Each arm 27 is pivoted to a wippen 29, as shown in Figs. 1 and 4, in such a 10 manner as to permit the several arms of the series to be freely depressed without affecting their respective wippens, while the movement of said wippens in actuating the hammers will force said arms downward at 15 every actuation. Any such depression of the lever arms 27 causes, by the consequent pressure of the spoons 26 against the tails 30 of the dampers, the removal of the associated dampers from their strings.

20 Each lever arm 27 is connected by a link 31 to an armature 32 pivotally supported just above an electro-magnet 33, of which there is a series, there being also a series of armatures, one facing each magnet. From 25 this arrangement it follows that energization of any electro-magnet of the series will result in the immediate attraction of its armature, and cause the connected lever arm 27 to be drawn down and to withdraw the 30 damper which it controls.

When the strings are being vibrated both electromagnetically and percussively, it is immaterial whether the electrical or the mechanical undamping acts first; but the construction described enables the damping and undamping to be performed mechanically when the electrical actuation of the strings is switched off; and enables the undamping to be performed electrically when the sticks 40 ers 19 are withdrawn from engagement with the hammer action and the instrument is being played electrically.

Each electromagnet 33 is wired to the proper contacts 13, 14 as by the wire 34, and 45 by a common lead wire 35 to said source of current 3. Hence the circuits to said electromagnets and to the electromagnets 2 have each a common section comprising a brush 15, contacts 13, 14 and resistance 12; and accordingly, upon the closing of a circuit for 50 delivering pulsatory currents to a string-vibrating electromagnet, the circuit is simultaneously closed by which non-pulsatory currents are delivered to the undamping 55 electromagnets.

In addition to the dampers 25 above described, a considerable number of the lower bass strings are each provided with a damper 40 located near the lower end of the 60 string, as shown in Fig. 1, the construction of each such damper being shown upon a larger scale in Figs. 2 and 3. Here it will be seen that the damper-felts are held by a short bar 41 carried by a wire 65 42, the latter being held by the bell-crank

lever 43 which is pivotally supported at 44. A spring 37 keeps the damper in normal contact with its associated string 1, while an electromagnet 45 acts upon a pivoted armature 46 connected by a link 47 to the short arm of said lever. Each said electromagnet 45 is connected by a wire 48 to its proper contact 14; as by having said wire 48 joined to a wire 10, and is also wired to the current-source 3, as by means of the 75 leads 49, 35. See Fig. 1.

The magnets and contacts being thus wired, it follows that whenever a key 17 is depressed or the parts of the action associated therewith are operated, and its associated brush 15 is brought into engagement with a contact 14, a pulsatory current flows to the associated electromagnet 2, and non-pulsatory currents pass to the connected electromagnets 33 and 45. The dampers 25 and 40 will hence be immediately withdrawn by the magnets 33 and 45 from the string controlled by the actuated key, and said string will be electrically vibrated by the magnet 2.

Inasmuch as it is necessary to cut away a part of the sounding board 50 in order to make room for the electromagnets 2, while the lower part of the sounding board can be run direct to the bridge supporting the 90 ends of the strings thereat, the lower ends of the strings consequently have a more pronounced sonorous effect upon the sounding board than their upper ends. For this reason, the auxiliary dampers 40 are more efficient in terminating the sonorous effect of the vibrations of their strings than are the upper dampers 25. In instruments where only the ordinary upper dampers are used, the undamped longer sections of the strings 100 may continue to vibrate for an appreciable time after the seating of the dampers, and affect the sounding board through the direct connection of their lower ends therewith. But when the lower tier of dampers is 110 used, the strings are instantly damped at their points of connection with the sounding board, and all sound therefrom promptly terminated. This complete termination is made more certain by the joint employment 105 of two dampers for each of the heavier bass strings.

Another advantage inherent with these auxiliary dampers is that they may be located at exactly the proper places on their 120 strings, whereas the upper dampers must accommodate the hammers. Again, sufficiently strong springs 37 can be used for the auxiliary dampers to properly damp their strings, since these dampers are withdrawn by electromagnetic means entirely 125 and the latter can be made as powerful as needed. The upper dampers, on the other hand, must not be given springs stronger than the key-controlled actions will allow. 130

The auxiliary dampers are all withdrawn from their strings by means of a suitable pedal (not shown) acting through a bar 51 (Fig. 2) pivotally supported at 52 and 5 swung forward against the bell-crank levers 43 by pressure against the arm 53, in substantially the usual manner.

It will be seen from the foregoing description that in the embodiment of the invention illustrated, the dampers constitute two sets or tiers, and that the dampers of each tier or set have mechanical means for their withdrawal, the means associated with the dampers of one tier or set being independent 15 of the means associated with the dampers of the other tier or set.

It may happen that, when the heavier bass strings are made to sound their most powerful notes for a considerable interval 20 of time, the vibrations will "build up" as it is called, and swing through such an amplitude of vibration as to strike their actuating electromagnets 2. To prevent this, we prefer to locate behind the strings near their 25 lower ends a board 55 having on its face a sheet of soft material 56 which is met by the strings whenever they exceed a suitably-safe amplitude of vibration. This board is not for the purpose of affecting the vibrations 30 in any other way, but is simply intended to restrain them from passing a safe amplitude.

Owing to the limited space between the strings, the magnets 33 of the upper series 35 are arranged in two rows or tiers and in staggered relation, so that the magnets of one tier alternate with those of the other, and the links 47 connecting the armatures 46 of the lower tier with the levers 43, pass 40 between the magnets and armatures of the upper tier. The same arrangement is for the like reason adopted for the lower magnets 45, and is clearly shown in Fig. 3. This Fig. 3 also illustrates another feature in 45 regard to the auxiliary dampers. As will be evident upon inspection, the levers 43 increase in length toward the right, the shortest lever acting to damp the lowest bass string, and the longer ones serving for 50 those progressively higher in pitch. The impressing springs 37, on the other hand, are shown of the same length for all the levers. The purpose is this: The springs being all of the same strength, the pressure 55 therefrom on the shortest lever comes so near the latter's free end as to produce a much stronger effect than does the spring of the right hand longest lever. The intermediate levers are correspondingly affected. 60 Consequently the heaviest strings are given the hardest damping-pressure, with lighter and lighter pressures for the strings ascending the scale.

While it might be possible to thus graduate 65 the damper pressure by keeping the

levers 43 all of the same length, and correspondingly varying the lengths of the springs 37, yet inasmuch as it is advisable to keep the dampers at the proper points of the progressively shortening strings, which 70 shortening is accomplished at their lower ends, it is better to maintain the pivotal points of the levers at a constant level and shorten their lengths as illustrated. Thus 75 this requirement operates in conjunction with the constant length of the springs to accomplish two distinct functions.

It is obvious that this instrument lends itself most readily to mechanical manipulation by means of traveling perforated 80 music rolls, and the like, as found in the mechanical players at present on the market, most of which operate to press the keys of the ordinary keyboard. Any means, however, of opening and closing the appropriate 85 electrical circuits, whether through the operation of the keys of the keyboard or otherwise, would come well within the scope of our invention, and whenever, therefore, we herein refer to "keys" we wish to be 90 understood to include within that term any mechanism operating to produce the results for which said keys are designed, as it is manifest that the various circuits of this instrument could be opened and closed me- 95 chanically, either with or without the use of a keyboard. We do not, therefore, limit ourselves either in this specification or the claims to an instrument operated only by the usual pressure of the keys of a key- 100 board, but desire to include any means by which this instrument may be operated by a mechanical or human player.

It is customary in the piano-type of musical instruments to employ either one, two 105 or three strings for a single note, but in the drawings, for the sake of clearness, but one string is represented for each note. The terms "sonorous body", and "string" are also employed in the specification and 110 claims as embracing a note of either one or a plurality of sonorous elements tuned in unison and used as a single note.

What we claim as our invention and for which we desire Letters Patent is as fol- 115 lows, to wit:—

1. The combination with sonorous bodies tuned to the notes of the musical scale, and with means for their vibration, of a series of damping devices, one for each of said 120 bodies; a second series of damping devices, one for each of certain of said bodies; mechanical means for operating each of the damping devices of the first series; and electrical means for operating the damping de- 125 vices of the second series.

2. The combination with sonorous bodies tuned to the notes of the musical scale, and means for their vibration, of a damping de- 130 vice associated with each of said bodies,

- second damping device associated with each of certain of said bodies, mechanical means for operating each of said first-mentioned damping devices independently, mechanical 5 means for operating all of said last-mentioned damping devices simultaneously, and electromagnetic means for withdrawing all of the dampers from a given body simultaneously.
- 10 3. The combination with sonorous strings tuned to the notes of the musical scale, of electromagnetic and percussive means for their vibration, dampers arranged to damp each of said strings adjacent the striking 15 point of the percussive means, other dampers located at a point equally distant from the other end of the string, and electromagnetic means for controlling all of the dampers of each of said strings simultaneously.
- 20 4. A musical instrument comprising sonorous bodies tuned to the notes of the musical scale; a plurality of dampers for each said body in a certain section of said instrument, normally in damping relation thereto, 25 said dampers being arranged in separate sets or tiers; mechanical means for withdrawing said dampers, the means associated with one set being independent of the means associated with the other set; means for vibrating 30 said sonorous bodies; and electromagnetic means arranged to be operated simultaneously with said vibration-producing means, to remove the several dampers from each sonorous body vibrated.
- 35 5. A musical instrument comprising tuned sonorous strings, electrical means for their vibration located near one end of said strings, depressible keys controlling the same, a damper for each string, an auxiliary damper for each of certain of the strings located near the other ends thereof, 40 and electromagnetic means controlled by said keys for withdrawing both dampers simultaneously from each of said strings.
- 45 6. A musical instrument comprising tuned sonorous bodies; electromagnetic means for their vibration including a source of current and circuit connections; keys controlling said circuit connections; a plurality of 50 mechanically independent dampers for each of certain of said sonorous bodies; and electromagnetic means forming parts of said circuit connections and controlling each
- damper, whereby the actuation of a single key causes the simultaneous vibration of its 55 associated sonorous body and the withdrawal of all the dampers therefrom.
7. A musical instrument comprising tuned sonorous bodies; electromagnetic means for their vibration including a source of current and circuit connections; a plurality of dampers for each of certain of said bodies; an electromagnet for each said damper; a source of current and circuit connections for 60 said electromagnets; a section of the circuit 65 connections of the damper-electromagnets and of the electromagnetic vibrating means of each sonorous body being common; and a brush associated with each said body for opening and closing the connections at the 70 common section.
8. A musical instrument comprising sonorous bodies tuned to the musical scale; means for vibrating said bodies, comprising an electromagnet and circuit for each such body, and a source of current for said circuits; a rheostat in each circuit; keys controlling said circuits; a plurality of dampers for each sonorous body and individual thereto; and individual electromagnets for 80 said several dampers, each in a branch of the circuit of the magnet which vibrates said sonorous body.
9. A musical instrument comprising tuned sonorous strings, electrical and percussive 85 means for their vibration, keys controlling their vibration, a damper for each string located close to the point where the latter is struck, an additional damper for each of certain of the strings located near the end 90 thereof farther from its striking point, and means whereby the depression of any key removes from its associated string both dampers contacting therewith.
- In testimony that we claim the foregoing 95 invention, we have hereunto set our hands this 11th and 16th days of July, 1910.
